TURNING MACHINE

George F. Yager, Toledo, Ohio, assignor to The Bunting Brass and Bronze Company, Toledo, Ohio, a corporation of Ohio

Application March 10, 1930. Serial No. 434,797

14 Claims. (Cl. 82—2)

This invention relates to metal working machines and has particular reference to machines for turning or otherwise fashioning bushings and the like.

5 One of the principal objects of this invention is to provide a machine of the type specified above which is thoroughly automatic in operation and which materially expedites production owing to the rapidity with which the same 10 operates.

Another object of this invention is to provide work holding means operable to position the work in proper relation to the tool irrespective of variations in dimensions of the work and to 15 associate with the holding means stripping mechanism for automatically releasing the work from the holder upon completion of the fashioning operation.

With the foregoing as well as other objects in 20 view the invention resides in the peculiar construction of machine and the expedient manner in which the same functions to fashion the work which will be made more apparent as this description proceeds, especially when considered in 25 connection with the accompanying drawings, wherein:

Figure 1 is a side elevational view partly in section of a machine constructed in accordance with my invention.

30 Figure 2 is an end elevational view partly in section of the machine illustrated in Figure 1.

Figure 3 is an enlarged sectional view through the work clamping means.

Figure 4 is a sectional view taken on the line 35 4—4 of Figure 1.

Figure 5 is a semi-diagrammatic view illustrating the mechanism for actuating the tool carriage.

Figure 6 is a sectional view taken on the line 40 6—6 of Figure 5.

Figure 7 is a sectional view taken on the line 7—7 of Figure 3.

Figure 8 is a sectional view taken on the line 8—8 of Figure 3.

45 Generally described, the machine illustrated herein is especially designed for turning bushings and the like to a predetermined diameter and comprises a frame 10 and a pair of coaxially arranged spindles 11 and 12 carried by 50 the heads 13 and 14, respectively, which in turn are slidably mounted upon the frame 10. The spindles 11 and 12 are mounted within the heads 13 and 14 for both reciprocable and rotative movements relative to the heads and are oper- 55 able in one position to engage opposite ends of

the bushing to clamp the same in operative position with the tool carrying slide 15. The tool carrying slide 15 is mounted for reciprocable movement in a path substantially parallel to the axis of the spindles 11 and 12 and is adapted to 60 carry a tool 16 for finishing the exterior surface of the bushing.

As will be more fully hereinafter described, the bushings are automatically fed to a suitable transfer device illustrated generally by the reference character 17 by means of the downwardly inclined chute 18. The transfer device is pivotally mounted upon a bracket 19 rigid with the head 14 and is adapted to be operated by a suitable cam in time relation to the movement 70 of the spindles 11 and 12 for releasing the bushing just completed to automatically transfer the bushing from the chute 18 to a position to be engaged by the work clamping means when the spindles are moved inwardly into operative 75 position. After the spindles have been moved to a position wherein the work is rigidly clamped in place, the tool carrying slide 15 is moved in a direction parallel to the axis of the bushing permitting the tool 16 carried thereby to move 80 across the face of the bushing. Upon completion of the aforesaid movement of the tool the spindles 13 and 14 are moved away from each other to release the bushing and the transfer device is actuated to place another bushing 85 in operative position with the clamping means. The successive operations of the transfer device spindles and tool slide 15 are so timed that upon one complete cycle of operation of the tool, two 90 bushings are completed.

Referring now more in detail to the specific construction of the machine illustrated and with special reference to Figure 1, it will be noted that the machine comprises a drive shaft 20 driven at a comparatively slow rate of speed 95 through the reduction gearing 21 by a stub shaft 22 having a pulley 23 thereon adapted to be connected to a suitable source of power (not shown). 24 is a stub shaft journaled in a bracket 24' rigid with the frame 10; 25 is a pinion on the stub shaft 24 and meshing with a gear 25' on a cam shaft 26 journaled at its opposite ends in brackets 24' and 26'; 27 and 27' are change gears rigid with the drive and stub shafts 20 and 24, and 28 is a clutch collar on the stub shaft 24 controlling the driving connection between the stub shaft 24 and pinion 25. 29 is a lever for actuating the clutch collar 28; 29' is a shaft journaled in the frame 10 for actuating 100 105 110

the lever 29, and 29'' is an operating lever for the shaft 29'.

Secured to the cam shaft 26 in spaced relation to each other are cam drums 30, 31 and 5 32. The cam drum 30 carries a pair of cams 33 and 34 respectively adapted to control the operation of the push rod 35 for moving the bushings into the transfer device 17 and the reciprocable movement of the spindle 12. The 10 cam drum 31 carries a cam 31' having a cam groove 36 adapted to control the reciprocable movement of the spindle 11 and is further provided with a cam surface 37 for controlling the operation of the transfer device. The cam drum 15 32 carries a cam 32' having a cam groove 38 for controlling the sliding movement of the tool carriage 15. The above described cam surfaces are all fashioned to perform the various operations in sequence and in timed relation to each other 20 as specified in the preceding description. The cam shaft 26 also has secured thereto a suitable brake mechanism 39 for maintaining the shaft steady during operation thereof.

In order to establish a connection between the 25 cam groove 33 and push rod 35 for reciprocating the latter, I provide a lever 40 pivotally mounted intermediate the ends thereof as at 41 to a bracket 41' rigid with the frame of the machine and having the lower end engaging 30 within the cam groove 33 and normally maintained in engagement with the cam surface by means of a suitable coil spring 42 having one end secured to the frame 10 and the opposite end secured to the lever 40 below the pivot 41. The 35 upper end of the lever 40 is secured to the outer end of the plunger 35 as at 43 for moving the same axially. The disposition of the plunger 35 upon the machine is such that upon inward movement of the same, it engages the lower- 40 most bushing on the chute 18 and moves the same into the transfer device 17.

After the bushing, above referred to, has been moved into the transfer device 17, the cam surface 37 swings the transfer device 17 about its 45 pivot 19' so as to position the bushing in operative relation between the spindles 11 and 12. The connection between the cam surface 37 and transfer device for accomplishing the above purpose comprises a bell crank lever 44 pivoted 50 at 45 upon a bracket 44' rigid with the frame of the machine and has the short arm 46 thereof extending at substantially right angles to the other arm 47 and engageable with the cam surface 37. The upper end of the lever 47 is connected by means of a rod 48 to the transfer device 17 at a point spaced from the pivot 19'. The cam surface 37 is so designed that upon one revolution thereof the transfer device 17 is operated twice to move a bushing in operative 55 relation between the spindles 11 and 12. Suitable adjustable stops 49 and 50 are provided for controlling the movement of the transfer device with the result that when the latter is in engagement with the stop 49, it will be in accurate 60 position to engage a bushing from the chute 18 and when in engagement with the stop 50, the bushing carried thereby will be in accurate alignment with the spindles. The transfer device 17 is mounted upon one side of the chute 70 and comprises a pair of pivotal jaws 51 and 52 normally urged into clamping engagement by suitable coil spring 53.

After the bushing, carried by the transfer device, is moved to operative position between the 75 spindles 11 and 12, the cam grooves 34 and 36

operate to move the spindles inwardly for clamping the bushing in place. The cam grooves 34 and 36 are respectively connected to the outer ends of the spindles 11 and 12 by means of levers 54 pivotally connected intermediate their ends as at 55 to the heads 13 and 14 and having the upper ends thereof connected to the outer ends of the spindles 11 and 12 in any suitable manner. The lower ends of the levers 54 are provided with sleeve-like extensions 56 having springs 57 therein surrounding the actuating rods 58. The actuating rods 58 extend axially through the sleeves 56 and the inner ends thereof have ball and socket connections with levers 58' pivoted upon brackets 41' and 44'. Rollers 56' carried by studs 56' in levers 58' travel in cam grooves 34 and 36. The outer ends of the rods 58 extend through the end walls of the machine frame and have square end portions adapted to be engaged by a suitable tool, whereby the rods 95 may be turned to effect the desired adjustment. As shown in Figure 1, I provide plungers 60 threadedly engaging the rods 58 intermediate the ends thereof and having portions extending within the sleeves 56 for engagement with the 100 inner ends of the springs 57. The outer ends of the springs 57 engage suitable closure members 61 surrounding and slidably mounted upon the rods 58. The arrangement is such that upon rotation of the rods 58, the plungers 60 will 105 function to rock the lever 54 about its pivot 55 to adjust the levers 54 and spindles 11 and 12 to compensate for bushings of various lengths. Likewise, rotation of the members 61 relative to the sleeves 56 varies the tension of the springs 113 57.

The cam grooves 34 and 36 are oppositely disposed so that the spindles 11 and 12 are simultaneously moved toward and away from each other. Moreover, as will be understood from the 115 foregoing description, the connections between the levers 54 and actuating rods 58 permit relative movement between the rods and the levers so that after sufficient pressure is exerted by the spindles on opposite ends of the bushing further 120 movement of the spindles toward each other is prevented and merely absorbed by the coil springs 57. By reason of this construction any 125 danger of deforming or otherwise effecting the contour of the bushing by the clamping operation is reduced to the minimum.

After the spindles 11 and 12 have been moved by the cam surfaces 34 and 36 to clamp a bushing therebetween, the cam surface 38 functions to move the tool carriage 15 substantially the 130 length of the bushing to permit the tool 16 carried thereby to finish the bushing. The connection between the cam groove 38 and tool carriage comprises a pair of levers 62 and 63 mounted upon the shafts 60' having the opposite ends journaled in brackets 62', 62'' rigid with the frame of the machine. The lever 62 has the upper end thereof operatively connected by a link 66 to the tool carriage 15 for actuating the latter and has a turnbuckle connection at its lower end to the lever 63 at the upper end thereof. The lower end of the lever 63 is pivoted to the bracket 63' and the upper end carries a suitable roller 64 that travels in the cam groove 38. Adjustment of the turnbuckle is 145 made to place the tool 16 in proper position to engage the work. Preferably the outer ends of the turnbuckle bolts 69 and 69' are slideable vertically in T slots 69'' in the levers 62 and 63 to vary the throw of the lever 62. Thus varia- 150

tion in the throw of the lever 62 causes a corresponding variation in the movement of the slide 15, whereby the tool 16 carried thereby may operate upon bushings of various lengths.

5 In this connection it is to be noted that the depth of cut of the tool 16 may be regulated by means of the screw 70 which is adapted to move the tool holder in a direction transverse to the direction of movement of the tool carriage.

10 After the bushing has been clamped in place by the spindles 11 and 12, the cam surface 37 operates to return the transfer device 17 to its inoperative position as shown in Figure 2, and 15 the carriage 15 is moved by the cam 38 in the manner set forth above to move the tool across the bushing. In this connection it is to be noted that the clamping force exerted by the spindles upon the bushing is substantially greater than the force exerted by the jaws 51 and 52 with the result that the latter will readily operate to release the bushing upon movement thereof to the position set forth above. After 20 the tool has been moved across the bushing, the cam surfaces 34 and 36 function to move the spindles 11 and 12 outwardly to release the work and permit the same to fall upon the discharge chute 72. When the foregoing operation is accomplished, the cam surface 33 operates to actuate the push rod 35 to move a bushing from the chute 18 into the jaws carried by the transfer device and the latter is moved by the cam surface 37 to position the bushing in proper position to be clamped between the spindles 11 and 12 upon movement thereof. The tool slide 15 is then caused to move back to its initial position during which time the tool 16 functions to finish the bushing to be operated upon. Thus, 25 from the foregoing it will be observed that the operation of the machine is thoroughly automatic and a bushing is completed upon each movement of the tool slide or, in other words, two bushings are completed upon one cycle of operation of the tool slide 15.

30 In order to compensate for bushings of various diameters, the cam 37 has a slotted connection with the cam drum 31 permitting the former to be adjusted to vary the operation of the transfer device 17. In this connection it will further be observed that the chute 18 may be angularly adjusted relative to its support so as to change the position of the delivery end thereof relative to the transfer device. As shown, the lower end portion of the chute is 35 provided with a depending projection 73 pivotally connected as at 74 to a bracket 74' slidable horizontally on the frame 10 of the machine and having a projection 75 extending substantially below the pivotal connection 74 and having universal engagement with a suitable adjusting device 76. The arrangement is such that movement of the projection 75 by the adjustable device rocks the chute 18 about the pivotal connection 74 to change the position of the delivery end thereof relative to the transfer device.

40 Referring now more in detail to the means upon the spindles 11 and 12 for clamping a bushing in operative position and with special reference to Figure 3, it will be noted that I provide arbors 77 and 78 secured within suitable recesses formed in the ends of the spindles 11 and 12, respectively, by means of the tie bars 79 extending through the spindles and secured 45 to the outer ends thereof by means of the nuts

80. In detail, the arbors 77 and 78 are provided with tapered portions 81 adapted to seat within the correspondingly shaped recesses formed in the ends of the spindles and are provided with inwardly extending projections 82 arranged concentric with the spindles and having openings 83 therethrough intermediate the ends thereof and extending transversely to the axis of rotation. The openings 83 are of sufficient dimension to receive the rockers 84 having semi-spherical outer faces 85 rockably engaging the outer walls 86 of the openings 83 and having inner substantially flat surfaces 87 for engagement with the bushing. The rockers are held in proper position within the openings 83 by means of pins 88 extending transversely through the openings 83 and adapted to engage within suitable slots 89 formed in the flat surfaces 87 of the rockers. The arrangement is such as to permit universal movement of the rockers 84 within the openings 83 relative to the arbors. When a bushing is clamped in place, as shown in Figure 3, the extreme inner ends of the projections 82 in advance of the rockers extend within the opposite ends of the bushing and are substantially the same diameter as the inner diameter of the bushing so as to accurately position the latter concentric with the axis of rotation. In this connection it will further be observed from the above figure that the substantially flat surfaces 87 of the rockers project beyond the opening 83 a sufficient distance to engage the end portions of the bushing. By virtue of this arrangement when the spindles 11 and 12 are moved inwardly, the bushing is rigidly clamped between the flat surfaces 87 of the rockers and owing to the fact that the latter are capable of universal movement relative to the arbors any irregularities in the ends of the bushing will be compensated for and will not affect the clamping action. The above construction permits turning the bushings to proper diameter prior to squaring the ends thereof and is one of the important features of this invention.

45 In order to facilitate release of the bushing from the arbors 82 upon movement of the spindles outwardly, I provide suitable stripping means which as shown in Figure 3 comprises substantially cup-shaped members 90 having enlarged tubular portions 91 surrounding the inner ends 92 of the spindles and having reduced inwardly extending tubular portions 93 surrounding the projections 82 of the arbors and slotted as at 94 to receive the projecting ends of the rockers 84. The extreme inner ends of the tubular portions 93 are yieldably maintained out of engagement with the opposite ends of the bushing by means of coil springs 95 arranged within recesses 96 formed in the inner end portions of the spindles. Each of the enlarged tubular portions 91 of the cup-shaped members 90 is provided with an adjustable collar 97. In use these collars are adapted to be held by clamp screws 97' in proper spaced relation to thrust bearings 97" so that engagement of the collars with the thrust bearings, when the cup-shaped members 90 are moved outwardly, causes the bushing to be stripped from arbors 82.

50 As shown more particularly in Figure 1, the heads 13 and 14 are also capable of adjustment to permit the machine to be utilized for fashioning bushings of different lengths. Preferably the heads 13 and 14 are slidable axially of the spindles 11 and 12 by means of the adjust-

able elements 98 carried by the frame 10 of the machine.

The spindles 11 and 12 may be rotated in any suitable manner but, as shown in Figure 1, are 5 preferably independently rotated from a suitable source of power. In detail, each of the spindles 11 and 12 have secured thereto intermediate the ends thereof a pulley 99 for receiving a suitable belt 100 extending from the source of 10 power. The belts 100 for rotating the spindles preferably extend through suitable slots formed in the upper portions of the slidable heads 13 and 14 and are enclosed by the guards 101 secured to the heads aforesaid.

15 Referring again to Figure 1 of the drawings, it will be noted that I have provided means for manually rotating the cam shaft 26 so as to facilitate initially setting up the machine. For 20 accomplishing this result, I provide a pinion 102 meshing with the cam shaft gear 25'. The pinion 102 is preferably secured to a stub shaft 103 having the outer ends thereof projecting through one end wall of the bracket 24' and squared for the reception of a suitable crank or other actuating member (not shown).

25 Thus, from the foregoing it will be observed that I have provided a machine which is thoroughly automatic in operation and one which materially expedites production owing to the 30 expedient manner in which the same functions to fashion the work. It will further be apparent that I have provided a machine of the type specified above having numerous adjustments which permit the same to be readily 35 utilized for fashioning articles of different dimensions and also that I have provided improved means for clamping the articles in the machine which compensates for any irregularities in the articles and which is entirely 40 automatic in operation.

While in describing the machine, illustrated herein, particular stress has been placed upon the association thereof for fashioning bushings, it should be understood that the inventive principles 45 involved herein may be employed in numerous metal working machines and reservation is made to make such changes in the construction as may come within the purview of the accompanying claims.

50 What I claim as my invention is:

1. In a machine for fashioning bushings and the like, the combination of a pair of co-axially extending arbors having circular end portions arranged to engage within the opposite ends of 55 the bushing and having transversely extending openings therethrough adjacent the end portions aforesaid, means for simultaneously reciprocating and rotating said arbors, and members mounted within said openings for rocking movement relative to the arbors and having portions engageable with the opposite ends of the bushing upon movement of the arbors toward each other to clamp the bushing in position therebetween and means automatically operable upon movement 60 of the arbors away from each other to strip the bushing from the circular end portions of the arbors.

2. In a machine for fashioning bushings and the like, the combination with a pair of co-axially extending spindles and means for simultaneously rotating and reciprocating said spindles, of arbors carried by said spindles having circular end portions operable upon movement 70 of the spindles toward each other to extend within opposite ends of the bushing, said arbors

further having transversely extending openings therethrough adjacent the end portions aforesaid, members mounted within the openings for rocking movement relative to the arbors and having portions engageable with the opposite ends of the bushing to clamp the same to the arbors, and strippers mounted for sliding movement independent of the spindles and normally yieldably maintained in engagement with the opposite ends of the bushing for stripping the latter from the circular end portions of the arbors upon movement of the spindles away from each other. 80 85

3. In a metal working machine, the combination with a pair of co-axially extending spindles and means for rotating and reciprocating said spindles, of arbors secured to the inner ends of each of said spindles and having portions projecting inwardly from the latter, clamping means upon the inwardly projecting portions of the arbors operable upon movement of the spindles inwardly to clamp the work in operative position, a pair of substantially cup-shaped members having enlarged tubular portions slidably engaging the inner end portions of the spindles and 90 having reduced tubular portions slidably engaging the inwardly projecting portions aforesaid of the arbors and contacting with the opposite ends of the work, and yieldable means normally urging said cup-shaped members inwardly into 95 engagement with opposite ends of the work for stripping the latter from the arbors upon movement of the spindles away from each other. 100

4. In a metal working machine, the combination with a support and a carriage slidably 110 mounted upon the support, a cam for automatically actuating said carriage, means establishing an operative connection between the cam and carriage including, a lever pivotally connected to the support intermediate the ends thereof and 115 having one end engaging the carriage and the opposite end terminating adjacent the cam, a second lever pivotally mounted upon the support adjacent the last-mentioned end of the lever aforesaid and having a portion engageable with 120 said cam for actuation thereby and an adjustable link establishing a connection between said levers for adjusting the position of the carriage relative to the support and for varying the stroke of the first-mentioned lever to adjust the reciprocable movement of the carriage. 125

5. In a machine for fashioning bushings and the like, the combination with means for clamping the bushing in place, of a tool carrying slide reciprocable in a path parallel to the axis of the 130 bushing, means for automatically reciprocating said slide a distance substantially equal to the length of the bushing including, a rotatable element having a cam surface, a lever pivotally connected to a support substantially below the 135 cam and having the upper end thereof engaging the cam surface, a second lever pivotally mounted intermediate the ends thereof and having the one end connected to the tool slide and the opposite end terminating adjacent the pivotal 140 connection of said first-mentioned lever to the support and means connecting the free end of the first-named lever to the second-mentioned lever intermediate the ends of the latter including an adjustable link operable to vary the 145 stroke of the first-mentioned lever for adjusting the stroke of the tool carrying slide.

6. In a machine of the class described, a frame, substantially aligned heads on the frame, spindles mounted for rotary and longitudinal move- 150

- ments in said heads, thrust bearings for the spindles carried by the heads, arbors for supporting a bushing carried by said spindles, and means for releasing the bushing from the arbors 5 including members having tubular portions sleeved upon the inner ends of said spindles and having reduced tubular portions sleeved upon the arbors, yieldable means carried by the spindles and urging the members away from each 10 other, and adjustable collars on the members engageable with the thrust bearing aforesaid when the spindles are moved longitudinally to strip a bushing from the arbors.
7. In a machine of the class described, a frame, 15 substantially aligned heads on the frame, spindles mounted for rotary and longitudinal movements in said heads, thrust bearings for said spindles carried by said heads, arbors for supporting a bushing carried by said spindles, rockers carried by said arbors for clamping engagement with a bushing on said arbors, and stripping means for releasing the bushing from the arbors, including tubular members sleeved upon the inner ends of the spindles and having reduced portions sleeved upon the arbors and slotted 20 to receive the rockers, and means on the members engageable with the thrust bearing aforesaid when the spindles are moved longitudinally to strip a bushing from the arbors.
- 30 8. In a machine of the class described, a frame, substantially aligned heads on the frame, spindles mounted for longitudinal movement in said heads, arbors for supporting a bushing carried by said spindles, and stripping means for releasing the bushing from the arbors including members having portions sleeved upon the inner ends of the spindles and having portions sleeved upon the arbors, yieldable means carried by the spindles urging the members away from each 35 other, rollers on the members, and means carried by the heads engageable by the collars when the spindles are moved longitudinally to cause the portions aforesaid sleeved upon the arbors to strip a bushing therefrom.
- 40 45 9. In a machine of the class described, a frame, substantially aligned heads on the frame, rotary spindles mounted in said heads for movement toward and away from each other, thrust bearings for the spindles carried by the heads, work engaging arbors carried by said spindles, means carried by the arbors and operable upon movement of the spindles toward each other to clamp work on the arbors, work engaging members mounted for longitudinal movement on the spindles, yieldable means associated with the spindles and members for holding the latter in spaced relation to the work, and means associated with the members and engageable with the bearings when the spindles are moved away from each other to cause the members to move longitudinally of the spindles and strip the work from the work clamping means and arbors.
- 50 55 10. In a machine of the class described, a frame, opposed rotary spindles mounted for longitudinal movement on said frame, work engaging arbors projecting endwise from the spindles, and work stripping means carried by the spindles and associated with the arbors and frame in such a way that work engaged by the arbors will be stripped therefrom upon move- 60 65
- ment of the spindles longitudinally in one direction relative to the frame.
11. In a machine of the class described, a frame, opposed rotary spindles mounted for longitudinal movement on said frame, work engaging arbors projecting endwise from the spindles, means carried by the spindles for stripping work from the arbors, means associated with said stripping means and spindles for normally holding the stripping means inoperative, and means carried by the stripping means and engageable with parts rigid with the frame when the spindles are moved longitudinally to cause the stripping means to operate. 80
12. In a machine of the class described, a frame, opposed rotary spindles mounted for longitudinal movement on said frame, work supporting arbors projecting endwise from the spindles, means carried by said arbors and operable upon movement of the spindles in one direction to clamp work on the arbors, and means associated with the spindles and parts rigid with the frame and operable upon movement of the spindles longitudinally in the opposite direction for stripping work from the clamping 95 means and arbors.
13. In a machine of the class described, a frame, substantially aligned heads on the frame, rotary spindles carried in said heads for movement toward and away from each other, thrust 100 bearings for the spindles carried by the heads, work engaging arbors carried by said spindles, means carried by the arbors and operable upon movement of the spindles toward each other to clamp work on the arbors, work engaging members mounted for longitudinal movement on the spindles, yieldable means associated with the spindles and members for holding the latter in spaced relation to the work, and means associated with the members and engageable with the 105 bearings when the spindles are moved away from each other to cause the members to move longitudinally of the spindles and strip the work from the work clamping means and arbors.
14. In a machine of the class described, a frame, substantially aligned heads on the frame, rotary spindles mounted in said heads for movement toward and away from each other, work engaging arbors carried by said spindles, means associated with the arbors and operable upon 110 movement of the spindles toward each other to hold the work in engagement with the arbors, work engaging members mounted for longitudinal movement on the spindles, means associated with the spindles and members for holding the latter inoperative when the work is held in engagement with the arbors, and means associated with the members and parts rigid with the frame and operable when the spindles are moved away from each other to cause the members to move longitudinally of the spindles and strip the work from the work holding means and arbors. 115
